W. A. STEVENS.

COMBINED PUTTY KNIFE AND NAIL EXTRACTOR.

APPLICATION FILED JAN. 16, 1917.

1,255,660.

Patented Feb. 5, 1918.

Inventor:

Walter A. Stevens,

by Harry Boot, James V. Varnum,
and George H. Hayes.

UNITED STATES PATENT OFFICE.

WALTER A. STEVENS, OF CAMBRIDGE, MASSACHUSETTS.

COMBINED PUTTY-KNIFE AND NAIL-EXTRACTOR.

1,255,660.

Specification of Letters Patent.

Patented Feb. 5, 1918.

Application filed January 16, 1917. Serial No. 142,732.

To all whom it may concern:

Be it known that I, WALTER A. STEVENS, a citizen of the United States of America, and a resident of Cambridge, in the county 5 of Middlesex and Commonwealth of Massachusetts, have invented an Improvement in Combined Putty-Knives and Nail-Extractors, of which the following description, in connection with the accompanying 10 drawings, is a specification, like characters on the drawings representing like parts.

This invention relates to combination tools, and has for its object more particularly to provide a combined putty-knife or 15 glazier's tool and tack, brad or nail extractor.

The objects and features of the invention will be best understood from the following description, taken in connection with the accompanying drawings, of a combined tool 20 embodying a preferred form of the invention selected for purposes of illustration, it being understood that the invention in its true scope is definitely set forth by the 25 claims.

In the drawings:

Figure 1 is a top plan view of a tool embodying one form of the invention;

Fig. 2 is a side elevation of the tool represented in Fig. 1;

Fig. 3 is a longitudinal central section on line 3—3 of Fig. 1;

Fig. 4 is a vertical cross section on line 4—4 of Fig. 1; and

Fig. 5 is a vertical cross section on line 5—5 of Fig. 1.

In the illustrative embodiment of the invention shown, the blade 2 of the putty-knife or glazier's tool is provided with a 40 shank portion 4 which may be secured in a handle 6 of wood or any other similar material by rivets 8, 8, or in any other suitable manner.

The metal blade 2 is provided with means 45 for extracting or pulling nails, brads or tacks, said means herein comprising an opening, Fig. 1, extending longitudinally of the blade and having a portion 10 large enough to give free passage to the head of 50 a nail or tack, and a narrower, more or less tapered portion 14 which extends preferably in the direction of the handle, as shown in Fig. 1. The edges of the portion 10 of the opening are preferably beveled, as 55 shown at 12, Figs. 1, 3 and 4. That portion of the blade in which the narrower opening

14 is provided will preferably be raised above the surface of said blade 2, so that the opposed edges of said narrower opening 14 will extend gradually upward from the 60 opening 10 to act as cams, as will be described. The edges of said narrower opening 14 are preferably beveled where they join the edges of the opening 10, so as to form a substantial continuation of the latter, and up to a point adjacent the highest 65 part of the raised portion of the blade throughout which the narrower slot extends.

The blade 2 will preferably be offset substantially as shown at 18 in Figs. 2 and 3, so as to bring the flat face of the blade 2 nearer the plane of the corresponding face of the handle and preferably substantially in the same plane as the latter.

To extract a tack, nail or other fastening having a head, with the aid of my putty-knife or glazier's tool, the blade 2 is placed as flat as possible upon the part from which the nail is to be extracted, with the beveled edge of the opening 10 turned upwardly and the head of the nail to be extracted within said opening 10. The tool is then moved forwardly, that is to say, in the direction of its front edge 20, Fig. 1, as indicated by the arrow in said figure, whereupon the beveled edges of the openings 10 and 14 will be introduced beneath the head of the nail, and the edges of said opening 14, by their upward inclination and consequent cam action, will quickly and readily extract the nail.

It will be noted that while the knife may be tipped about its forward edge 20 to assist in extracting the nail, this is rarely if 95 ever necessary, the upwardly inclined edges of the opening 14, by their cam action on the head of the nail, produced by the forward movement of the knife, being sufficient to extract the nail or tack without any tipping of the knife. This is a great advantage when extracting nails from relatively soft or finished surfaces, as thereby all marring of said surface, as is often caused by the edge of the knife when the latter is tipped, 100 is avoided.

To extract a brad or other headless nail or fastening, the projecting part of the brad or nail is introduced between the edges of the narrower opening 14, that side of the 110 blade 2 from which the edges of said slot are raised being turned downwardly, so that

the projecting part of the brad or nail is embraced between said raised or cam edges of the slot 14. The knife is then tilted transversely, whereupon the edges of the 5 narrow slot 14 clamp the brad upon opposite sides, with an action which may be compared to that of a Stillson wrench, so that by further tipping said blade transversely, or by raising it while maintaining it sufficiently inclined toward one side or the 10 other to preserve the clamping action on the nail, the latter will be readily extracted.

As the edges of the slot 14 project beyond the face of the knife, it will be seen 15 that headless brads or nails that have been driven well home are readily seized and extracted with my tool.

The offset arrangement 18 greatly facilitates the extraction of nails from large 20 surfaces, as will be readily understood, in that it enables the under surface of the knife to be brought closer to the surface from which the nail is to be extracted.

It will be apparent to those skilled in the 25 art, from the above description, that my improved tool possesses many advantages over those of a similar nature heretofore used, and it is to be understood that while the invention is herein described as embodied 30 in the details illustrated, it is not to be considered as circumscribed by or limited to said details or any of them, but that said details may be modified in accordance with the true scope of the invention as set forth 35 in the claims.

Claims:

1. As a new article of manufacture, a nail or brad extracting implement, comprising 40 a flat blade provided with an extruded portion forming an indentation upon one face of said blade and upon the other side a projection presenting a surface inclined to the plane of the blade lengthwise the latter, the face of the blade that is presented 45 to the surface containing the nail being flat and a handle offset away from said flat face, thereby permitting the presentation

of said flat face flatwise to the said surface containing the nail throughout the length of said blade, said inclined surface 50 being provided with a tapered slot having its wide end at the base of said surface, so that by placing the face of the blade containing the indentation flat upon a surface containing a nail with the head of the latter in the wider portion of said tapered slot and sliding said blade longitudinally to cause the head of the nail to enter the narrower portion of said slot, the upwardly inclined edges of the latter will act on said 60 head to extract the nail from said surface.

2. As a new article of manufacture, a nail or brad extracting implement, comprising a flat blade provided with an extruded portion forming an indentation upon one side 65 of said blade and upon the other face a projection presenting a surface inclined to the plane of the blade lengthwise the latter and containing a tapered slot having its wider end at the base of said surface, 70 so that by inserting the head of a brad in the narrower portion of said slot and tilting the blade transversely upon the surface containing said brad, the latter will be extracted, while by placing the face of the 75 blade containing the indentation flat upon a surface containing a nail with the head of the latter in the wider portion of said tapered slot and sliding said blade longitudinally to cause the head of the nail to 80 enter the narrower portion of said slot, the upwardly inclined edges of the latter will act on said head to extract the nail from said surface, the face of the blade that is presented to the surface containing the nail 85 being flat and a handle offset away from said flat face, thereby permitting the presentation of said flat face flatwise to the said surface containing the nail throughout the length of said blade.

In testimony whereof, I have signed my name to this specification.

WALTER A. STEVENS.

Copies of this patent may be obtained for five cents each, by addressing the "Commissioner of Patents, Washington, D. C."

It is hereby certified that in Letters Patent No. 1,255,660, granted February 5, 1918, upon the application of Walter A. Stevens, of Cambridge, Massachusetts, for an improvement in "Combined Putty-Knives and Nail-Extractors," an error appears in the printed specification requiring correction as follows: Page 2, lines 41 and 65, claims 1 and 2, for the word "side" read *face*; and that the said Letters Patent should be read with this correction therein that the same may conform to the record of the case in the Patent Office.

Signed and sealed this 16th day of April, A. D., 1918.

[SEAL.]

F. W. H. CLAY,

Acting Commissioner of Patents.
